(57) **CLAIM**

We claim the ornamental design for a bicycle carrier rack, as shown and described.

DESCRIPTION

FIG. 1 is a perspective view of a bicycle carrier rack removably attached to an automotive vehicle;
FIG. 2 is a perspective view of a bicycle carrier rack;
FIG. 3 is a left side elevational view thereof;
FIG. 4 is right side elevational view thereof;
FIG. 5 is a front elevational view thereof;
FIG. 6 is a rear elevational view thereof; and,
FIG. 7 is a cross-sectional view taken along line 7-7 of FIG. 6. The dashed lines in FIG. 1 are directed to environment and are for illustrative purposes only; the broken lines depict unclaimed portions of the bicycle carrier rack. The dashed lines and the broken lines form no part of the claimed design.
